COMBINED DUST-RIDDING AND SAND-RECLAIMING SHIELD

Arthur A. Dick, Towson, Md.

Application August 1, 1947, Serial No. 765,586

3 Claims. (Cl. 51—8)

1

This invention relates to a combined dust-ridding and sand-reclaiming shield.

The primary purpose and object of this invention is to enable a user to clean or abrade the surface of a black-board or other substantially vertical surface with a sand-blast without filling the adjacent air with dust and without wasting sand or covering the adjacent floor and other objects with the sand that has been used in the sand-blast.

Another object is to provide means to conduct the dust away from the place of operation, to any appropriate place of disposal, and to provide appropriate means to catch the used sand in a movable receptacle for use over and over in the sand-blast.

Another object is to provide windows and light-entrances, so the user can watch the result of the sand-blast as he directs it to all points within the scope of the shield at each of its different adjusted positions.

Another object is to provide the shield with resilient or conformable lining-portions that project beyond the walls' free edges, so they can be pressed against the surface to be cleaned or abraded, thereby to prevent escape of dust or sand past the said free edges.

Another object is to provide the shield with a sand-outlet whose margin is of rubber or other conformable material, and which normally extends down into a sand-recovering vessel and conforms to the inner-upper surface of the latter so as to prevent escape of dust past said upper-inner surface.

Another object is to provide a wheel-supported frame for supporting the shield and facilitating its easy sliding adjustment to various points of the surface to be cleaned or abraded.

Another object is to provide the front wall of the shield with a conformable element having a hand-hole therethrough so it conforms to the wrist of the user whose hand holds and manipulates the sand-blast nozzle within the shield; thereby to prevent dust from escaping through the hand-hole.

Other objects and important features are pointed or implied in the following details of description in connection with the accompanying drawings in which:

Fig. 1 is a front view of a floor-supported form of the shield and its supporting frame in proper position to shield a part of the black-board, parts of the dust-conducting pipe, sand-receiving vessel and the black-board, being broken away.

Fig. 2 is a central vertical sectional view along the line 2—2 of Fig. 1, a part of the cushion-lining

2

being broken out to show a portion of the adjacent metal part of the side-wall.

Fig. 3 is an enlarged sectional view of the conformable inlet-element or hand-hole element and its adjuncts.

Referring to these drawings in detail, in which, similar reference numerals and letters refer to similar parts throughout the several views, the invention is described in detail as follows:

10 In broad terms, the invention comprises a shield or receiver that comprises a front wall 7 having therethrough an entrance-element 7e adapted to receive a sand-blast nozzle or a user's hand which manipulates the said nozzle, side-walls 8 having front-edges hermetically united with said front-wall at opposite sides of the entrance-element 7e, a bottom-wall 9 and a top-wall 10 each having front and lateral edges hermetically united with said front-wall and side-walls at 11, said side-walls and bottom-wall and top-wall having free conformable rear edges 12 substantially in a common upright plane and adapted to be held against and slid along a black-board or other plane upright surface S to be cleaned by a blast of sand and air through said entrance-element and directed at different parts of said surface, a dust-outlet-pipe 13 in open communication with the upper portion of said receiver, said bottom-wall having a depression 14 to assist in trapping sand to be used over and over in the sand-blast, said front wall 7 having a hermetic window through which a user can see the surface being cleaned or abraded.

The entrance-element 7e comprises a sheet of 35 rubber or other conformable material having therethrough a relatively small opening 10 through which a sand-blast-nozzle or a user's hand can be forced into said receiver, the conformable material of said entrance-element being 40 adapted to contract around the object forced therethrough, thereby to prevent escape of dust through said entrance-element during sand-blast operations.

In Figs. 1 and 2, the depression 14 has a sand-outlet 14o at its lower end, and a movable imperforate receptacle 15 is normally in open communication with said sand-outlet and hermetically connected thereto by a conformable endless edge-portion 14e, fitting in the upper end of the receptacle 15 so as to prevent escape of dust between said sand-outlet and movable receptacle.

Inner portions of the receiver are composed of rubber or other cushioning material 19 that resists abrasion by accidental contact with the sand-blast during operation thereof.

In Figs. 1 and 2, the supporting frame 20 in-

cludes a horizontal portion 20h adapted to support the imperforate receptacle 15, said frame comprising legs 20l having their upper portions united with said receiver and supporting the latter sufficiently above said horizontal portion to permit said receptacle 15 to be slid on said horizontal portion into and out of hermetic engagement with said sand-outlet 14o.

The supporting means or frame 20 is provided with wheels 20w to roll on an extrinsic support while said receiver is being slid along the surface being sand-blasted.

In Figs. 1 and 2, the wheels roll on the floor F.

Handle 7h is provided on the front-wall of the shield or receiver, so the operator can use this handle for pressing the guard or receiver against the surface being cleaned or abraded, and for rolling the device along the floor.

A window 81, or light-opening can be provided in either or both side-walls 8. The provision and positions of these light-entrances 81 is important because of the shadow that the operator may throw across the front window 1w.

The protective linings may be applied to the entire inner surface of the shield, as shown in Figs. 1 and 2. Although I have shown mechanical means such as metal strips secured by screws s and bolts b, other appropriate means, such as cement or adhesive material may be employed for securing the protective lining in place.

I have no intention to confine or limit my patent protection to the precise details of construction, materials and combination as described in the foregoing, and as shown in the drawings, for the invention is susceptible of numerous changes within the scope of the inventive ideas, as implied and claimed.

What I claim as my invention is:

1. In combination, a dust-ridging and sand-reclaiming shield for use with a sand-blast in cleaning substantially plane surfaces, said shield including a receiver that comprises a front-wall having therethrough an entrance-element adapted to receive a sand-blast nozzle or a user's hand which manipulates the said nozzle, side-walls having front-edges hermetically united with said front-wall at opposite sides of said entrance-element, a bottom-wall and a top-wall each having front and lateral edges hermetically united with said front-wall and side-walls, said side-walls and bottom-wall and top-wall having free conformable rear edges substantially in a common upright plane and adapted to be held against and slid along a black-board or other plane upright surface to be cleaned by a blast of sand and air through said entrance-element and directed at different parts of said surface, said re-

ceiver having a sand-outlet at its lower end, and a removable imperforate receptacle normally in open communication with said sand-outlet and hermetically connected thereto so as to prevent escape of dust from said receptacle or from between the latter and the sand-outlet.

2. The combination defined by claim 1, and a supporting frame that includes a horizontal portion adapted to support said receptacle, said frame comprising legs having their upper portions united with said receiver and supporting the latter sufficiently above said horizontal portion to permit said receptacle to be slid on said horizontal portion into and out of hermetic engagement with said sand-outlet.

3. In combination, a supporting frame having a lower end that is free from a floor or other substantially level surface on which it is adapted to be supported for movement thereon, said frame including a shelf above said lower end and adapted to hold a receptacle in a proper relation to be removed therefrom, and a shield that includes a receiver that comprises a front wall having therethrough an entrance element adapted to receive a sand-blast nozzle and/or a user's hand that manipulates said nozzle, said shield having side-walls comprising front edges hermetically united with said front wall at opposite sides of said entrance-element, said shield having a bottom-wall and a top wall, said side-walls and bottom-wall and top wall having free conformable rear edges substantially in a common upright plane and adapted to be held against and slid along a black-board to be cleaned by a blast of sand and air thru said entrance element and directed against different parts of said blackboard, said receiver having an outlet above said shelf and having the upper part of said supporting frame united with its lower end-portion in a proper relation to communicate said outlet with said receptacle when the latter is on said shelf.
